ELECTRIC HAIR CLIPPER

John F. Wahl and Leo J. Wahl, Sterling, Ill., assignors to Wahl Clipper Corporation, Sterling, Ill., a corporation of Illinois

Application February 6, 1956, Serial No. 40,046

Term of patent 14 years

(Cl. D22—3)

Fig. 1

Fig. 2.

Fig. 3.

Fig. 1 is a top plan view of an electric hair clipper showing our new design;

Fig. 2 is an elevational view of one side thereof, and
Fig. 3 is an elevational view of the other side thereof.
The bottom of the clipper is plain and unornamented.
We claim:

The ornamental design for an electric hair clipper, as shown and described.
